(57) **CLAIM**

The ornamental design for a drawer safe, as shown and described.

DESCRIPTION

FIG. 1 is a perspective view of a drawer safe showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a left-side elevational view thereof;

FIG. 7 is a right-side elevational view thereof;

FIG. 8 is a perspective view of the drawer shown separately for ease of illustration;

FIG. 9 is a front elevational view of FIG. 8;

FIG. 10 is a top plan view of FIG. 8;

FIG. 11 is a bottom plan view of FIG. 8;

FIG. 12 is a rear elevational view of FIG. 8;

FIG. 13 is a left-side elevational view of FIG. 8;

FIG. 14 is a right-side elevational view of FIG. 8;

FIG. 15 is a perspective view of the safe enclosure shown separately for ease of illustration;

FIG. 16 is a front elevational view of FIG. 15;

FIG. 17 is a top plan view of FIG. 15;

FIG. 18 is a bottom plan view of FIG. 15;

FIG. 19 is a rear elevational view of FIG. 15;

FIG. 20 is a left-side elevational view of FIG. 15; and,

FIG. 21 is a right-side elevational view of FIG. 15.

The broken lines in the figures represent environmental matter, and form no part of the claimed design.
